(57) **CLAIM**

The ornamental design of a compact, self contained condition monitoring device for monitoring the operation of a pump, a fan, compressor, turbine or other rotating or reciprocating piece of machinery, as shown and described.

DESCRIPTION

FIG. 1 is a top perspective view of a compact, self contained condition monitoring device showing the present invention; FIG. 2 is a left side view of the compact, self contained condition monitoring device in FIG. 1 showing the present invention;

FIG. 3 is a right side view of the compact, self contained condition monitoring device in FIG. 1 showing the present invention;

FIG. 4 is a top view of the compact, self contained condition monitoring device in FIG. 1 showing the present invention; FIG. 5 is a back view of the compact, self contained condition monitoring device in FIG. 1 showing the present invention;

FIG. 6 is a front side view of the compact, self contained condition monitoring device in FIG. 1 the present invention; and,

FIG. 7 is a back side of the compact, self contained condition monitoring device in FIG. 1 showing the present invention.
